US0D1097334S

(12) **United States Design Patent** (10) **Patent No.:** **US D1,097,334 S**
(45) **Date of Patent:** **** Oct. 7, 2025**

(54) **HAIR ATTACHMENT**

(71) Applicant: **KANEKA CORPORATION**, Osaka (JP)

(72) Inventor: **Yoshihiko Okayama**, Accra (GH)

(73) Assignee: **Kaneka Corporation**, Osaka (JP)

(**) Term: **15 Years**

(21) Appl. No.: **29/909,860**

(22) Filed: **Aug. 11, 2023**

(30) **Foreign Application Priority Data**

Feb. 21, 2023 (JP) ..... 2023-003250 D

(51) **LOC (15) Cl.** **28-04**

(52) **U.S. Cl.**

USPC **D28/92**

(58) **Field of Classification Search**

USPC D28/92, 93; D2/867, 899, 894

(57) **CLAIM**

The ornamental design for a hair attachment as shown and described.

DESCRIPTION

FIG. 1 is a top perspective view of a hair attachment showing the claimed design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

In the drawings, the broken lines show portions of the hair attachment that form no part of the claimed design.

1 Claim, 4 Drawing Sheets
